RESISTOR UNIT

Donald F. Hastings, Fairlawn, N. J., assignor to
Hardwick, Hindle, Inc., Newark, N. J.

Application September 22, 1937, Serial No. 165,104

7 Claims. (Cl. 201—67)

This invention relates to an improved form of resistance unit especially adapted for mounting in spring clips.

The principal object of my invention is to provide an improved method of mounting the terminal contact members on the unit and making electrical connection therewith from the resistance winding.

While attaining the principal object of my invention, it is a further object to simplify the construction and reduce the cost of manufacture.

My improved form of construction will be readily understood by reference to the annexed drawing, wherein:

15 Figure 1 is a plan view of the completely assembled resistance unit, the outer covering over the resistance winding being omitted at the ends where the winding is connected to the terminals.

20 Figure 2 is an enlarged, longitudinal, sectional view through the left end of the device shown in Figure 1.

Figure 3 is a view on the line 3—3 of Figure 2.

Figure 4 is a plan view of the filler strip used in mounting the contact ferrule onto the resistance unit.

25 In the various views, wherein like numbers refer to corresponding parts, 1 is a core, preferably hollow to provide ventilation. The core is made of high-heat-resisting and insulating material, preferably of ceramic nature, on which is located a winding 2 of any satisfactory resistance wire. After the winding 2 is put on, it is preferably covered with a vitreous enamel coating 3. On each end of the core 1 is mounted a 30 band ferrule 4 which is preferably made of a non-corrosive material, such as Monel metal, which has a low temperature coefficient of expansion.

35 In forming the ferrule or cup 4, the edge or rim 5 is preferably turned over, as shown in Figure 2, to provide a smooth annular shoulder which acts as a guide and stop for assisting in locating the unit on its spring member mounting. The opposite end of the ferrule 4 has a flange 6 40 of a width sufficient to overlap the end of the core to mechanically protect the core and at the same time fix the location of the ferrule on the core. In order to hold the ferrule 4 on the end of the core 1, a metallic filler strip 7, shown in detail in Figure 4, is used. The strip 7 is provided with a plurality of spaced ribs or bosses 8 45 which are formed outwardly from the body of the strip 7, as more particularly shown in Figure 2. The strip or shim 7 is preferably made of relatively soft metal having a high-temperature co-

5 efficient of expansion, such as copper. The shim or filler strip is preferably provided with a plurality of wire-wrapping cleats 9, the function of which will be presently described.

10 The thickness of the strip 7 and the height of the bosses or ribs 8 are made compatible with the internal diameter of the ferrule 4 and the outside diameter of the end of the core 1, but I have found, in practice, that by using the copper strip having a thickness of .008" to .010", and bosses 10 or ribs having a total depth of approximately .020", that when the ferrule 4 is forced into place over the end of the core 1, as shown in Figure 2, it being understood that the strip 7 is 15 folded up circularly and placed within the ferrule 4 before the same is forced over the end of the core 1, this type of filler strip or shim compensates for normal variations in the outside diameter of the core 1 and inside diameter of the ferrule 4, it being understood that the ferrule 4 20 is made to have an internal diameter compatible with the size of the core 1 to be used, the idea being to secure a tight fit between the ferrule and the end of the core 1, through the medium of a 25 filler strip as heretofore described.

30 After the ferrule 4 and its associated filler strip have been assembled to the core 1, one end of the winding 2 is wrapped around a cleat 9, preferably in a diagonal or crosswise manner, after which the wire is brazed or soldered with hard solder to the cleat 9 which, as shown in Figures 1 and 2, projects a short distance beyond the rim 5 of the ferrule. It sometimes occurs that the resistance 2 is required to be very accurate and even an additional inch or half-inch of winding is objectionable. Therefore, to better meet this condition, a plurality of cleats 9 are provided on the strip 7 so that the resistance wire 35 may be terminated at any one of these cleats, it being understood that I prefer to put the winding 2 onto the core 1 after the ferrules 4 have been mounted in position.

40 I have found that by constructing the ferrule 4 and shim 7 of the materials and mounting them in the manner heretofore described, provides such a satisfactory union that after the vitreous enamel 3 is applied to the winding 2, the high temperature required for firing or baking this vitreous enamel covering, will not loosen the union. In the application of the outer covering, 45 this is preferably extended to completely cover the cleats 9 and the connection of the winding thereto, as well as to seal the joint around the rim 5, somewhat as indicated at 10 in Figure 2. While I have specified an outer covering of vitre- 50

ous enamel, for certain purposes some other type of covering, such as cement or insulating varnish, may be used.

In the past it has been the practice to connect the end of the resistance winding to a stranded copper wire which is also wrapped around the core, and then connect this copper wire to a clip on the ferrules which are held to the core by cementing or by a through bolt; but by my 10 method of construction and assembly as described herein, I have greatly simplified and improved the general arrangement of the resistance unit.

What I claim is:

- 15 1. A resistance unit including a core member of heat-resisting and insulating material having a winding thereon but spaced from the ends of the core and covered with a coating of baked vitreous material, a metallic band ferrule located on each end of the core adjacent the termination of the winding, and means for holding the ferrule in place, said means comprising a metallic filler strip coiled to the approximate internal diameter of the ferrule and located therein, said filler strip having a plurality of transverse ribs normally projecting from the plane of the strip so when the core ends are forced into the ferrules the ribs provide sufficient gripping to hold the ferrules securely in place at all times, including that of baking the covering, and means for electrically connecting the ends of the winding to the ferrules before the said baked coating is applied.
- 20 2. A resistance unit as set forth in claim 1, further characterized in that one edge of the filler strip is provided with at least one wire-wrapping cleat which projects beyond the inner end of the ferrule to receive one end of the winding.
- 25 3. A resistance unit as set forth in claim 1, further characterized in that the ferrule comprises a cup of non-corrosive metal having a low temperature coefficient of expansion, while the filler strip is of relatively soft metal having a high temperature coefficient of expansion.
- 30 4. A resistance unit as set forth in claim 1, further characterized in that the ferrule comprises a cup of drawn Monel metal having an end flange of a width to overlap the core and a turned over

rim, while the filler strip is of copper having a plurality of projecting cleats for wrapping the end of the winding therearound.

5. A resistance unit including a tubular core of ceramic material having a winding thereon but spaced from the ends of the core, a metallic band ferrule located on each end of the core adjacent an end of the winding, a metallic filler strip of good current-conducting material having a plurality of normally transverse ribs, coiled within 10 the ferrule, the ribs acting to take up variations within limits in the outside diameter of the core ends and inside diameter of the ferrules, and to hold the ferrules securely and permanently in place on the core when the core ends and ferrules 15 are pressed into operative position, said filler strip having at least one wire-attaching cleat projecting beyond the inner end of its associated ferrule for attachment of an end of the winding thereto.

6. A resistance unit as defined in claim 5, further characterized in that the band ferrules are made of metal having a low temperature coefficient of expansion, while the filler strips have a high temperature coefficient of expansion.

7. A resistance unit including a core member of 25 heat-resisting and insulating material having a winding thereon but spaced from the ends of the core, a metallic band ferrule located on each end of the core adjacent the termination of the winding, and means for permanently holding the ferrule in place, said means comprising a metallic filler strip arcuately fitting within the ferrule, said strip carrying means projecting from the plane of the strip so when the core ends are forced into the ferrules said means carried on the strip provide 30 sufficient gripping to hold the ferrules securely in place, and means for electrically connecting the ends of the winding to the ferrules, so the resistance of the unit will be very accurate, said means comprising a plurality of arcuately 35 arranged cleats integral with the strip and projecting beyond the inner edge of its associated ferrule, whereby a cleat may be selected for attachment on the end of the winding which will give the desired resistance to the unit.
